UNITED STATES PATENT OFFICE.

NATHANIEL B. POST, OF CHICAGO, ILLINOIS.

POP-CORN MOLD.

1,421,555.

Specification of Letters Patent.

Patented July 4, 1922.

Application filed October 29, 1919. Serial No. 334,131.

To all whom it may concern:

Be it known that I, NATHANIEL B. POST, a citizen of the United States, and a resident of the city of Chicago, county of Cook, 5 and State of Illinois, have invented certain new and useful Improvements in Pop-Corn Molds, of which the following is a specification.

My invention relates to improvements in 10 pop corn molds, and has for its object the provision of a simple and efficient device of this character by means of which pop corn balls may be formed with great ease and expedition.

Other objects will appear hereinafter.

The invention consists in the combinations and arrangements of parts herein-after described and claimed.

The invention will be best understood by 20 reference to the accompanying drawings forming a part of this specification, and in which

Fig. 1, is an end view of an apparatus embodying the invention,

Fig. 2, a transverse section of the same,

Fig. 3, a top plan view of the same, and

Fig. 4, a longitudinal section taken on line 4-4 of Fig. 3.

The preferred form of construction, as 30 illustrated in the drawings, comprises a suitable table 5 having a mold member secured centrally to the top thereof, said mold member being formed of a strip of sheet metal, bent as indicated, to form a plurality 35 of semi-cylindrical mold recesses 6, the ends of said strip being bent to form flanges 7 which are secured to the table top to hold the mold member in place. A mold board 8 is swingingly mounted on the table top 40 5, being carried by arms 9 pivoted on brackets 10 secured to the table top, and said mold board being provided with an operating handle 11 for convenience in manipulating the same. Stop pins 12 are 45 also secured to brackets 10 in position to limit the upward swing of said mold board for convenience in operation. A second mold member is secured to the under side of the mold board 8, said second mold member 50 also consisting of a strip of sheet metal bent to form a plurality of semi-cylindrical mold recesses 13, supplementary to the recesses 6, the ends 14 of said strip being secured to the ends of the mold board 8, 55 as shown. The arrangement is such that when the mold board 8 is swung down-

wardly into operative relation with the table top, the recesses 13 co-operate with the recesses 6 to form cylindrical mold chambers open at their opposite ends, so 60 that the pop corn material placed in and over the mold recesses 6 will be thus compressed into cylindrical forms. A suitable housing 15 is secured to the table top and arranged about the mold recesses 6 to retain material therein when first placed in the apparatus. 65

Arranged in each of the cylindrical mold chambers thus provided is a pair of mold heads 16, each provided with a spherical 70 mold recess 17 in its inner face, the arrangement being such that when said mold heads are brought together a ball will be formed of the material in the corresponding cylindrical mold chamber, as best indicated in 75 Fig. 2. An operating bar 18 extends across the top of the table 5 adjacent the open ends of the cylindrical mold chambers, and all of the mold heads 16 operating in the corresponding ends of the cylindrical mold 80 chambers are secured to the corresponding operating bar so as to compel simultaneous operation thereof. Operating levers 19 are pivoted at 20 to the table 5 and project upwardly through slots 21 provided in 85 the table top, the upper ends of said levers being pivoted to the corresponding operating bars 18. The levers 19 are connected by links 22 with oppositely arranged eccentric crank pins on the discs or plates 23 90 secured to an operating shaft 24 mounted longitudinally in the table top and between the sets of levers 19. This operating shaft 24 is provided with an operating crank handle 25, by means of which the same may 95 be oscillated when desired.

In use, the mold board 8 is first swung upwardly until the arms 9 rest against the stop pins 12 and the mold heads 16 are withdrawn into the positions indicated in 100 Fig. 1. Thereupon a proper amount of pop corn material is poured into and over the mold recesses 6 and the mold board 8 swung back into horizontal position, thus causing the mold recesses 13, co-operating 105 with the recesses 6, to form the pop corn material into substantially cylindrical bodies within the various mold chambers and between the mold heads 16. Thereupon the mold heads 16 are forced together by 110 operation of the crank handle 25, and this material further compressed into balls.

The mold board 8 is then swung upwardly out of the way, and the mold heads 16 separated, whereupon the balls may be readily removed. In this way pop corn 5 or similar material may be readily and quickly formed into balls. The specific form and arrangement of parts disclosed is a simple and effective one for the purpose.

While I have illustrated and described 10 the preferred form of construction for carrying my invention into effect, this is capable of variation and modification without departing from the spirit of the invention. I, therefore, do not wish to be limited 15 to the precise details of construction set forth, but desire to avail myself of such variations and modifications as come within the scope of the appended claims.

Having described my invention, what I 20 claim as new and desire to secure by Letters Patent is:—

1. A mold comprising a support; a mold member rigidly mounted on said support and provided at one side with a mold recess 25 therein open at its ends; a mold board pivotally mounted on said support to swing into and out of operative position with relation to said first mentioned mold member; a mold member secured to said mold 30 board and provided with a mold recess co-operating with said first named recess to form a mold chamber open at its opposite ends; a pair of oppositely arranged mold heads slidably mounted in said mold chamber; and means for simultaneously forcing 35 said mold heads toward and away from each other, substantially as described.

2. A mold comprising a support; a mold member rigidly mounted on said support 40 and provided with a cylindrical mold recess therein open at its ends; a mold board pivotally mounted on said support to swing into and out of operative position with relation to said first mentioned mold member; a mold member secured to said mold board 45 and provided with a cylindrical mold recess co-operating with said first named recess to form a mold chamber open at its opposite ends; a pair of oppositely arranged hemispherical mold heads slidably mounted in said mold chamber; and means for simultaneously forcing 50 said mold heads toward or away from each other, substantially as described.

55 3. A mold comprising a support; a mold member rigidly mounted on said support and provided in its upper side with a plurality of mold recesses therein open at their ends; a mold board pivotally mounted on 60 said support to swing into and out of operative position above said first-mentioned mold member; a mold member secured to the under side of said mold board and provided in its under face with a plurality of mold recesses 65 co-operating with said first-named re-

cesses to form mold chambers open at their opposite ends; a pair of oppositely arranged mold heads slidably mounted in each of said mold chambers; and means for simultaneously forcing said mold heads toward and away from each other, substantially as described.

4. A mold comprising a support; a mold member rigidly mounted on said support and provided in its upper side with a plurality of mold recesses therein open at their ends; a mold board pivotally mounted on said support to swing into and out of operative position above said first-mentioned mold member; a mold member secured to the under side of said mold board and provided in its under face with a plurality of mold recesses co-operating with said first-named recesses to form mold chambers open at their opposite ends; a pair of oppositely arranged mold heads slidably mounted in each of said mold chambers; an operating bar secured to all of the mold heads in the corresponding ends of said mold chambers; levers fulcrumed on said support and operatively connected with said bars; and means for simultaneously forcing said levers toward and away from each other, substantially as described.

5. A mold comprising a support; a mold member rigidly mounted on said support and provided in its upper side with a plurality of semi-cylindrical mold recesses therein open at their ends; a mold board pivotally mounted on said support to swing into and out of operative position above said first mentioned mold member; a mold member secured to the under side of said mold board and provided in its under face with a plurality of semi-cylindrical mold recesses co-operating with said first mentioned recesses to form cylindrical mold chambers open at their opposite ends; a pair of oppositely arranged hemispherical mold heads slidably mounted in each of said mold chambers; an operating bar secured to all of the mold heads in the corresponding ends of said mold chambers, and means for simultaneously forcing said bars toward and away from each other, substantially as described.

6. A mold comprising a support; a mold member rigidly mounted on said support and provided in its upper side with a plurality of semi-cylindrical mold recesses therein open at their ends; a mold board pivotally mounted on said support to swing into and out of operative position above said first mentioned mold member; a mold member secured to the under side of said mold board and provided in its under face with a plurality of semi-cylindrical mold recesses co-operating with said first mentioned recesses to form cylindrical mold chambers open at their opposite ends; a pair of oppositely arranged hemispherical mold heads slidably

mounted in each of said mold chambers; an operating bar secured to all of the mold heads in the corresponding ends of said mold chambers; two pairs of co-operating 5 levers pivoted to said table below the top thereof and projecting upwardly through said table and pivotally secured to said bars, there being slots in the table top to accommodate said levers; an operating shaft 10 mounted below said table between the members of said pairs of levers; oppositely arranged eccentric crank pins on said shaft; links connecting said crank pins with said levers; and means for oscillating said shaft to force said operating bars simultaneously 15 toward and away from each other, substantially as described.

In testimony whereof I have signed my name to this specification in the presence of two subscribing witnesses.
